UNITED STATES PATENT OFFICE.

JUNE W. GAYLE, OF OWENTON, KENTUCKY.

METHOD OF TREATING LEAF-TOBACCO.

1,180,137.

Specification of Letters Patent. Patented Apr. 18, 1916.

No Drawing.

Application filed April 7, 1915. Serial No. 19,766.

To all whom it may concern:

Be it known that I, JUNE W. GAYLE, a citizen of the United States, residing at Owenton, in the county of Owen and State 5 of Kentucky, have invented certain new and useful Improvements in Methods of Treating Leaf-Tobacco; and I do hereby declare the following to be a full, clear, and exact description of the invention, such as will 10 enable others skilled in the art to which it appertains to make and use the same.

This invention relates to certain new and useful improvements in methods of treating funked, house-burned or otherwise damaged leaf tobacco and restoring the same to 15 its natural state and at the same time purifying, bleaching and brightening the leaves, the process being designed for treating tobacco used for either smoking or chewing.

20 In carrying out my process, the tobacco leaves to be treated are suspended within a suitable steam tight chamber and subjected for a period of approximately thirty minutes to the action of steam admitted to 25 the chamber. The tobacco having been thus moistened by the action of steam is sub-

jected for a period of from one to four hours, the time depending upon the condition of the leaves to be treated, to the fumes of sulfur or brimstone, in the production of 30 which fumes either brimstone, stick or lump sulfur are burned in a separate compartment, the fumes being admitted to the chamber containing the leaves to be treated.

Having thus described my process, what 35 I claim to be new and desire to secure by Letters Patent is:

The herein described method of treating, damaged leaf tobacco and restoring the same to its natural state, which consists in 40 suspending the same within a steam-tight receptacle, subjecting the same to the action of steam until it is thoroughly moistened, then subjecting the same to sulfur fumes for a period of from two to eight times that of 45 moistening.

In testimony whereof I hereunto affix my signature in presence of two witnesses.

JUNE W. GAYLE.

Witnesses:

JAMES GAYLE,
E. R. TRAMMELL.
